UNITED STATES PATENT OFFICE.

JOHN J. PHARE, OF CLEVELAND, OHIO, ASSIGNOR TO ZULA C. HODGES, OF CLEVELAND, OHIO.

MOP-HOLDER.

1,132,524.

Specification of Letters Patent.

Patented Mar. 16, 1915.

Application filed April 22, 1912. Serial No. 692,346.

To all whom it may concern:

Be it known that I, JOHN J. PHARE, a citizen of the United States, residing at Cleveland, in the county of Cuyahoga and 5 State of Ohio, have invented certain new and useful Improvements in Mop-Holders, of which the following is a specification.

My invention relates to mop holders and has for its object the provision of a mop 10 holder comprising a head having improved means for securing the mop thereto consisting of hooked members pivotally mounted thereon and adapted to engage the mop.

My invention will be described in detail 15 hereinafter and illustrated in the accompanying drawings, in which,

Figure 1 is a front view of a mop head and mop in a clamped position thereon; Fig. 2, a side view; Fig. 3, a longitudinal sec- 20 tional view of the mop head; and Fig. 4, a detail view of a modified form of engaging members.

My invention relates to mop heads for holding sanitary mops such as used in hospitals and the like, that are usually constructed with a transverse web holding the fibers of the mop together in their middles. The construction of mop heads for these mops heretofore has made it necessary to 25 provide the transverse web with eyeleted holes, and my invention provides for securing a mop to the head to the exclusion of the use of the eyeleted holes.

In the drawings, I have illustrated the 30 preferred form of my invention, and similar reference characters will be used to designate corresponding parts throughout the several views.

My improved mop head consists of a casting indicated generally at 1 having a socket 40 2 to receive the end of a handle A that is secured thereto by a rivet or other fastening means *a*. The cross bar of the mop head is as shown, formed with a longitudinal channel 45 with its sides preferably inclined toward one another, the longitudinal bar being indicated generally at 3 and the inclined sides at 4.

5 indicated braces connecting the outer 50 ends of the cross head 3 with the socket member 2, said braces being spaced apart as shown at 6. I preferably form said mop head from a sheet metal blank bent into the shape described, though, I do not con- 55 fine myself to this structure. Secured in

the middle of the cross head 3 is a cork screw shaped pin 7 to engage the transverse web 8 of the mop 9.

10 indicates lever arms that in Figs. 1, 2 and 3 are formed with eye-loops 11 pivotally secured to the flanges 4 of the cross bar 3 by means of the pins 12, said lever arms being provided on their lower ends with hook-shaped points 13, while their upper ends are formed with inwardly inclined 60 portions 14, then upwardly inclined portions 15, and their upper terminals formed with outwardly extending portions 16 that form finger holds for grasping the levers and operating them. When the levers are in an 70 operative position, it will be understood as shown by the drawings that the upright portions 15 engage the sides of the handle A where engaged by the socket 2, the inwardly inclined portions 14 permitting said engagement, while the finger-hold portions 16 extend outwardly from the handle to enable the operator to easily grasp the lever for swinging it away from the handle to release the mop.

The cross bar 3 is provided with slots 17 to receive the hooks 13 and permit movement of the hooks in swinging the levers to release the mop. In use, it will be understood that to secure the mop to the head the levers 85 are swung into their outward position to withdraw the hooks from the mop head, and after the screw pin 7 has been inserted in the web 8, the levers 16 are then swung over into the position shown in Fig. 1 and the 90 mop will be securely fastened to the head. To release the mop it will be apparent that a reversal of the operation just described is only necessary and said operation can be accomplished without necessitating grasping the mop with the hands.

In Fig. 4 I have illustrated a modified form of the lever, in which the lever is constructed of sheet metal and indicated generally at 21, the hooked portion being des- 100 ignated 22 while 23 indicates an integral lug formed with an opening 24 to receive the pin on the mop head designated 12 in Figs. 1, 2 and 3.

Having thus described my invention what 105 I claim is:—

1. A mop holder comprising a head, sharp pointed hooks pivoted thereto and provided with handles, the points of said hooks being adapted on movement of the handles in one 110

direction, first to pierce the mop and then to draw the same against the mop head.

2. In a mop holder, a head, hooks pivotally secured to said head and projecting therefrom, said hooks being provided with sharp engaging points that are adapted to pierce the mop and moving in the direction away from the middle of the mop head and engaging the mop fabric to stretch said fabric thereon.

3. A mop holder comprising a cross bar and a socket adapted to engage the handle of the mop, said cross bar having slots therein, and hooks pivotally engaging said cross bar and operating in said slots to engage a mop.

4. A mop holder comprising a socket adapted to engage the end of a handle, a cross bar on said socket, said cross bar being provided with longitudinal slots, levers pivotally secured to said cross bar, and hooks

formed integral with said levers and operating in said slots, said hooks having sharp engaging points that are adapted to engage a mop.

5. A mop holder comprising a socket to engage the end of a handle, a cross bar on said socket, said cross bar being provided with longitudinal slots, a cork screw-shaped pin secured intermediate of the ends of said cross bar, levers pivotally secured to said cross bar, and hooks formed integral with said levers and operating in said slots, said hooks and pin being adapted to engage a mop.

In testimony whereof I affix my signature in presence of two witnesses.

JOHN J. PHARE.
